LIP PROTECTOR DEVICE

Nathan Malerman, Forest Hills, N. Y.

Application August 10, 1946, Serial No. 689,772

6 Claims. (Cl. 2—174)

1

This invention relates to devices for shielding or guarding the lips of the mouth to protect the same against sun and wind to prevent the same from becoming sunburned, windburned or otherwise abused by exposure to the elements. More particularly, the invention deals with a device of the character described fashioned to fit snugly, but freely, on the lips and in the mouth and, in such manner, as to provide certain uses of the mouth in a more or less natural state. The novel features of the invention will be best understood from the following description, when taken together with the accompanying drawing, in which certain embodiments of the invention are disclosed and, in which, the separate parts are designated by suitable reference characters in each of the views and, in which:

Fig. 1 is a diagrammatic view of the front, lower portion of the face illustrating one of my improved protector devices in position on the mouth.

Fig. 2 is a section on the line 2—2 of Fig. 1.

Fig. 3 is a section substantially on the line 3—3 with the lip protecting device shown in its entirety.

Fig. 4 is a section on the line 4—4 of Fig. 1, omitting the lip or mouth portion and diagrammatically illustrating in dotted lines movement of the device into open position.

In Fig. 1 of the drawing, I have indicated at 10 the lower chin and mouth portion of a face and, in Fig. 2, 11 indicates the upper lip; 12 the lower lip. In Fig. 3 of the drawing, 13 and 14 represent the side, corner portions of the mouth. At 15 is shown one of my improved protector devices.

The device 15 comprises an upper lip shield or guard portion or member 16 and a lower lip shield or guard portion or member 17. The member 16 has an upper double curved edge portion 18 of "cupid's bow" contour; whereas the member 17 has a rounded, lower edge portion 19, these edge portions substantially conforming with the contour of the mouth extending over the lip portions 11 and 12 sufficiently to cover and shield outer surfaces thereof. Adjacent edge portions 20, 21 of the members 16 and 17 are rounded or curved, as seen, for example, at 22 in Fig. 3 of the drawing, so as to expose the major portion of adjacent surfaces 11', 12' of the lips in order to establish a direct contact with an article placed in the mouth, such for example as the cigarette 23, shown in Fig. 2 of the drawing. This illustration of holding the cigarette in the mouth is only

2

illustrative of the principle of the direct lip-engagement with an object.

Each of the members 16 and 17, at side portions thereof, have inwardly extending walls, both walls of the member 16 being shown at 24 in Fig. 3 of the drawing and one wall of the member 17 being shown at 25 in Fig. 4 of the drawing. These walls are also indicated in Fig. 2 of the drawing. The walls 24 and 25 are joined in spring-loop members 26, which extend beyond the ends of the members 16 and 17, as clearly noted in Fig. 3 of the drawing and the walls 24 and 25 are notched, for example, as seen at 27 in Fig. 3 of the drawing, so as to fit snugly in the corners of the mouth while allowing the members 26 to extend into the mouth beyond the corners 13 and 14, so as to retain the device against accidental displacement from the mouth. The members 16 and 17 are curved vertically, as well as longitudinally, to conform with the curvatures of the mouth, as clearly seen in Figs. 2 and 3 of the drawing. These curvatures also aid in retaining the members 16 and 17 upon the lips of the wearer, allowing the members 16 and 17 to move toward and from each other in the movement of the lips and through the action of the spring-loops 26. This movement is diagrammatically illustrated in the full and dotted line position shown in Fig. 4 of the drawing. The notches 27 form relatively narrow necks 28 which minimize the spring action, so that there is no real force required to separate the members 16 and 17, the inturned upper edge portion 29 of the member 16 and inturned lower edge portion 30 of the member 17 retaining the two members upon the lips, as will clearly appear from a consideration of Fig. 2 of the drawing.

The device can be constructed of any suitable material and may be made of plastic, in which latter case, the same can be of a color consistent with the normal lip coloring, so as to present a neat and finished appearance when used by the wearer.

It will also be apparent that the device may be constructed of very thin material, so as to be substantially unnoticeable upon the face and, in this sense, flexible to flex with the mouth in the movement thereof, so that the device will not interfere with normal conversation or normal lip movement. From this standpoint, it is possible that a device of the kind under consideration can be used for other purposes than simply a protector or shield, for which it is primarily intended. In other words, a device of this kind may be utilized as a medium for characterizing

or enhancing the lips of a wearer, dispensing with the necessity of applying rouge or lip markings, particularly by theatrical folks. In these other uses, the material employed can be of a more flexible character and constructed of a soft plastic material, rather than what might be termed a hard or rigid plastic material.

Having fully described my invention, what I claim as new and desire to secure by Letters Patent is:

1. A lip shield device, said device comprising two lip covering parts adapted for arrangement upon outer surfaces of the lips of the mouth, said parts having edges conforming to the general contour of the mouth, means at end extremities only of said parts for yieldably coupling the same to provide movement of the parts toward and from each other in corresponding movement of the lips, and adjacent edge portions of said parts having rounded edges extending to said ends forming openings exposing inner surfaces of the lips for direct contact one with respect to the other when said parts are in close proximity to each other.

2. A lip shield device, said device comprising two lip covering parts adapted for arrangement upon outer surfaces of the lips of the mouth, said parts having edges conforming to the general contour of the mouth, means at end portions of said parts for yieldably coupling the same to provide movement of the parts toward and from each other in corresponding movement of the lips, adjacent edge portions of said parts having rounded edges extending to said ends forming openings exposing inner surfaces of the lips for direct contact one with respect to the other when said parts are in close proximity to each other, and end portions of said devices having notches forming outwardly projecting members on said means extending into the mouth at corner portions of the lips in retaining the device against displacement from the lips.

3. A lip shield device, said device comprising two lip covering parts adapted for arrangement upon outer surfaces of the lips of the mouth, said parts having edges conforming to the general contour of the mouth, means at end portions of said parts for yieldably coupling the same to provide movement of the parts toward and from each other in corresponding movement of the lips, adjacent edge portions of said parts having rounded edges extending to said ends forming openings exposing inner surfaces of the

lips for direct contact one with respect to the other when said parts are in close proximity to each other, end portions of said devices having notches forming outwardly projecting members on said means extending into the mouth at corner portions of the lips in retaining the device against displacement from the lips, and said parts being of curved cross-sectional form.

4. A guard device for the lips of the mouth, 10 said device comprising a pair of lip covering parts shaped to conform with the contour of the lips, end portions of said parts having inwardly extending adjacent wall portions each joined in a spring-loop providing movement of said parts 15 toward and from each other, said walls being recessed to form notches adapted to engage the corners of the mouth at intersections of upper and lower lips in retaining the device against displacement from the lips, and the central portions 20 of said parts being open inwardly of adjacent edges thereof to expose the lips for direct contact with each other and with an object placed between the lips.

5. A lip guard of the character described comprising a pair of parts adapted to be arranged upon and to shield outer surface portions of the lips, and means projecting at ends of said parts for yieldably coupling said parts to facilitate movement thereof toward and from each other and for maintaining said parts against displacement from the mouth.

6. A lip guard of the character described comprising a pair of parts adapted to be arranged upon and to shield outer surface portions of the lips, means projecting at ends of said parts for yieldably coupling said parts to facilitate movement thereof toward and from each other and for maintaining said parts against displacement from the mouth, and the central portion of said parts between said means being open throughout the major portion of the length thereof for exposure of inner adjacent portions of the lips to contact one with the other.
